US00D934205S

(12) **United States Design Patent** (10) **Patent No.:** **US D934,205 S**
(45) **Date of Patent:** ** *Oct. 26, 2021

(54) **EARPIECE**

(71) Applicant: **Apple Inc.**, Cupertino, CA (US)

(72) Inventors: **Robert Brunner**, Glen Ellen, CA (US);
Christopher Kuh, San Francisco, CA (US); **Achille Biteur**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/774,949**

(22) Filed: **Mar. 19, 2021**

Related U.S. Application Data

(57)

CLAIM

The ornamental design for an earpiece, as shown and described.

DESCRIPTION

FIG. 1 is a perspective view of an earpiece showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dashed broken lines in the figures show portions of the earpiece that form no part of the claimed design.

The dot-dash broken lines in the figures show boundaries that form no part of the claimed design.

1 Claim, 2 Drawing Sheets
